Smith and Michael.

Attorneys.

UNITED STATES PATENT OFFICE.

HENRY W. BRENT, OF BALTIMORE, MARYLAND.

WINDOW-SHADE BRACKET.

Application filed May 18, 1925. Serial No. 31,121.

To all whom it may concern:

Be it known that I, HENRY W. BRENT, a citizen of the United States of America, residing at Baltimore, in the State of Maryland, have invented certain new and useful Improvements in Window-Shade Brackets, of which the following is a specification, reference being had therein to the accompanying drawing.

10 My invention relates to window shade brackets, and has particular reference to that class of shade bracket in which the bracket arm or arms are adjustable longitudinally to readily accommodate and support shade rollers of different lengths.

An object of my invention is to provide an improved form of base plate adapted for attachment to the vertical side members of a window or door frame, preferably near the 20 upper portion thereof, and to associate with said base plate an improved bracket arm slidably mounted on said base plate to be readily adjustable thereon to accommodate and support shade rollers of different 25 lengths.

A further object of my invention is to provide a base plate and improved means for securely attaching the same to the door or window frame, and to associate with the 30 base plate a bracket arm longitudinally adjustable thereon, and a novel fastening clip coacting with the base plate and bracket arm for rigidly maintaining said bracket arm in its adjusted position on the base plate.

35 A still further object of my invention is to provide an adjustable window shade bracket all parts of which may be stamped from sheet metal, and which is simple in construction, inexpensive to manufacture, reliable in operation, and strong and durable.

In the accompanying drawings forming a part of this specification and in which like numerals are employed to designate like parts throughout the several views:—

45 Fig. 1 is a broken longitudinal sectional view through the upper portion of a door or window frame above my improved bracket, showing the relative position of parts when assembled to support a window shade,

Fig. 2 is a vertical sectional view on the line 2—2 of Fig. 1,

Fig. 3 is a perspective view of my improved base plate,

Fig. 4 is a perspective view of the bar to 55 be associated with the base plate to secure the same to the door or window frame,

Fig. 5 is a fragmental elevational view of the base plate with the bracket and fastening clip positioned thereon, 60

Fig. 6 is a perspective view of the improved bracket arm,

Fig. 7 is a perspective view of the fastening clip, and

Fig. 8 is a plan view of the sheet metal 65 blank from which the fastening clip is formed.

Referring to the drawings, wherein for the purpose of illustration is shown a preferred embodiment of my invention, the numerals 1 and 2 indicate the left and right vertical side members respectively of a door or window frame of ordinary construction. Attached to each of the side frames 1 and 2 is a base plate 3, the two base plates preferably having their inner ends flush with the inner edge of the frame, and both being positioned in horizontal alignment near the upper portion of the said side frames. The detailed construction of the base plate 3 is 70 readily apparent from Fig. 3 of the accompanying drawings, from which it will be seen that the same comprises a base portion 4 having outwardly extending top and bottom portions 5 and 6, each terminating respectively in the upwardly and downwardly extending flanges 7 and 8. The edges of the flanges 7 and 8 are provided with teeth or notches 9, and the entire base plate in its finished form is capable of being stamped 75 from sheet metal, although the same may be readily cast and machined if desired. The base portion 4 is provided with spaced apertures 10 through which screws, nails or other fastening means may pass.

In Fig. 4 is shown a bar 11, rectangular in cross section, and of such dimensions as to tightly fit within the base plate 3 between the upper and lower flanges 5 and 6. This bar, which is of wood or other non-metallic material, is provided with spaced apertures 12 adapted to register with the apertures 10 when the base plate and bar are assembled. When it is desired to secure the base plate 3 to the side members 1 or 2 of the window 80 or door frame, the wooden or other non-metallic bar 11 is positioned between the flanges 5 and 6 and is forced back until it contacts

with the base portion 4, the apertures 12 registering with the apertures 10 in the base plate 3. The assembled base plate and bar are then placed in position on the frame and 5 screws or nails driven through the registering openings and into the frame, the heads of said screws or nails being forced or driven into the wooden or other non-metallic bar 11. Such an arrangement of parts enables 10 the base plates to be firmly and rigidly secured to the frames, and the bar aids materially in strengthening the sheet metal base plate and assisting it to withstand the strains and jars to which it is necessarily 15 subjected when in use.

My improved shade supporting bracket arm consists of a substantially T-shaped sheet metal member 13, provided near its outer end with an aperture 14, into which 20 the end bearing 15 of the window shade 16 is inserted. The back of the bracket arm 13 is provided with an inwardly extending, substantially T-shaped notch 17 of a size and shape such that the bracket arm may be 25 slipped endwise on the base plate 3, with the flanges 5 and 6 closely fitting and contacting with the top and bottom of the notch 17 and with the flanges 7 and 8 closely fitting within the ends of the T-shaped notch 17. The lower end of the bracket arm 13 is extended to form a foot 18 adapted to bear on the face of the window or door frame to prevent the downward movement of the bracket and to relieve the strain on the upper flange 7. The said bracket arm 13 is further provided with elongated notches 19 and 20 and with an indentation 21 for purposes to be hereinafter described.

My improved fastening clip for maintaining the bracket arm 13 in its adjusted position on the base plate 3, comprises a resilient clip 22 stamped from sheet metal in the form shown in Fig. 8 and bent into the form shown in Fig. 7. The mid portion of 40 the clip 22 is provided with an inwardly extending projection 23 formed by the use of a suitable die during the stamping operation, and the space between the long side walls of the clip, when in the form shown in Fig. 7 is slightly less than the thickness of the bracket arm 13, so that when the clip is 45 slipped on to the bracket arm 13, the said side walls will frictionally engage the sides of the bracket arm and the projection 23 will 50 drop or spring into the corresponding depression 21 formed in the side wall of the bracket arm. The inner ends of the upper and lower sides of the clip 22 are provided 55 with notches 24 and 25 respectively of a depth substantially that of the distance between the ends of the slots 19 and 20 and the back edge of the bracket 13.

In the use of my improved adjustable bracket above described, the base plate 3 and bar 11 are assembled and placed in the de-

sired position on the door or window frame. Nails or screws are passed through the registering apertures 12 and 10 and into the sash frame. The bracket arm 13 is then slipped endwise onto the base plate 3 and 70 moved along until the distance between the bracket arm on opposite sides of the door or window frame is proper to accommodate and support the end bearings 15 of the shade 16. The resilient clip 22 is then 75 slipped over the outer end of the bracket arm 13 and forced rearwardly until the upper and lower side walls of the inner ends of the clip move between the teeth on opposite sides of the bracket arm and the notches 24 80 and 25 fit into the notches 19 and 20, and the projection 23 springs into the indentation 21. The tapered shape of the top and bottom edges of the bracket 13 is such that the clip 22 is readily guided into position 85 on the bracket and within the upper and lower slots 19 and 20 respectively.

It will thus be seen that I have provided a window shade bracket which may be adjusted longitudinally of the door or window 90 frame to accommodate and support shade rollers of different lengths. The bracket, when assembled and secured to the frame as above described, comprises an unusually firm and rigid bracket and one that will not be 95 loosened or pulled from the frame by the weight of the shade or roller and the downward pulls and strains to which such a bracket is necessarily subjected when in use. The non-metallic bar 11 fitting within the 100 base plate 3 between the upper and lower sections 5 and 6 thereof, constitutes an especially satisfactory means for rigidly attaching the base plate to the frame. The 105 nails or screws passing through the apertures 12 and 10 of the bar and base plate respectively, may be driven or forced into the bar so that the heads thereof become imbedded in the non-metallic material of the 110 bar. This non-metallic bar thus serves to prevent a metal-to-metal contact between the heads of the screws or nails and the base plate 3, and also serves, due to the rectangular cross section of the bar, to support and 115 strengthen the upper and lower sections 5 and 6 of the base plate. The provision of the depending foot section 18 on the bracket arm 13 also serves to materially strengthen the bracket, due to the contact of the elongated foot section with the outer surface of the door or window frame, and the 120 tapered shape of the bracket arm assists the proper guiding of the resilient clip 22 into the slots 19 and 20 and between the teeth 9 on the flanges 7 and 8.

It is to be understood that the form of my invention herein shown and described is to be taken as a preferred embodiment of the same, and that various changes in the shape, size and arrangement of parts may be 125 re- 130

sorted to without departing from the spirit of the invention or the scope of the subjoined claims.

Having thus described my invention, I

5 claim:

1. A window shade bracket comprising a base plate having upwardly and downwardly extending toothed flanges, a bracket arm slidably mounted on the base plate, and a detachable fastening clip slidably mounted on the bracket arm and engaging the teeth of the upper and lower flanges to maintain the bracket arm in adjusted position on said base plate.
- 10 2. A window shade bracket comprising a base plate having upwardly and downwardly extending toothed flanges, a bracket arm slidably mounted on said base plate, and a detachable fastening clip slidably mounted on said base plate and adapted to engage the teeth of the upper and lower flanges on opposite sides of the bracket arm to maintain said bracket arm in adjusted position on said base plate.
- 15 3. A window shade bracket comprising a base plate, a bracket arm slidably mounted on said base plate, a resilient fastening clip slidably mounted on said bracket arm and engaging the base plate to maintain said bracket arm in adjusted position on said base plate, and means for retaining said resilient clip in locking position on said bracket arm.
- 20 4. A window shade bracket comprising a base plate, a bracket slidably mounted on said base plate and having an indentation in the side wall thereof, and a fastening clip mounted on said bracket arm and having a projection on a side wall thereof, the said fastening clip engaging the base plate for maintaining the bracket in adjusted position and the indentation on the base plate and

projection on the fastening clip co-acting to maintain the fastening clip in locking position on the bracket arm.

45

5. A window shade bracket comprising a base plate having upwardly and downwardly extending toothed flanges, a bracket arm slidably longitudinally of said base plate, a resilient fastening clip slidably mounted on the bracket arm and engaging the teeth on the upper and lower flanges on opposite sides of said bracket arm to maintain the bracket arm in adjusted position, and means for retaining the clip in locking position on said bracket arm.

50

6. A window shade bracket comprising a base plate having upwardly and downwardly extending toothed flanges, a bracket arm slidably mounted on said base plate, and a one-piece resilient fastening clip slidably mounted on said bracket arm and having spaced side walls adapted to engage the teeth on the upper and lower toothed flanges on opposite sides of the bracket arm to maintain the bracket arm in adjusted position on the base plate.

60

7. A window shade bracket comprising a base plate having upwardly and downwardly extending toothed flanges, a bracket arm slidably longitudinally on said base plate and having elongated notches near its upper and lower portions, and a detachable fastening clip slidably mounted on said bracket arm having spaced side walls adapted to engage the teeth on the upper and lower toothed flanges on opposite sides of the bracket arm, the top and bottom walls of said fastening clip resting within the said elongated notches in the bracket arm when the clip is in locking position.

70

In testimony whereof I hereunto affix my signature.

HENRY W. BRENT.
